DESIGN FOR A CHILD'S GARMENT HANGER

Ingvelde Rappaport, New York, N. Y.

Application July 12, 1944, Serial No. 114,379

Term of patent 3½ years

(Cl. D80—8)

To all whom it may concern:

Be it known that I, Ingvelde Rappaport, a citizen of Austria, residing at New York, in the county of New York, State of New York, have invented a new, original, and ornamental Design for a Child's Garment Hanger, of which the following is a specification, reference being had to the accompanying drawing, forming part thereof.

I claim:

The ornamental design of a child's garment hanger, as shown and described.

INGVELDE RAPPAPORT.
